(57) **CLAIM**

The ornamental design for a bolt cutter handle, as shown and described.

DESCRIPTION

FIG. 1 is a front, top and right side perspective view of a bolt cutter handle embodying our new design;
FIG. 2 is a front, bottom and left side perspective view thereof;

FIG. 3 is a bottom plan view thereof;

FIG. 4 is a top plan view thereof;

FIG. 5 is a right side elevation view thereof;

FIG. 6 is a left side elevation view thereof;

FIG. 7 is a front elevation view thereof;

FIG. 8 is a rear elevation view thereof; and,

FIG. 9 is a perspective view of the bolt cutter handle in a configuration of use.

The broken lines of the bolt cutter handle in FIGS. 1-9 are illustrative of portions of the bolt cutter handle that form no part of the claimed design. In FIG. 9, the broken line showing of a bolt cutter depicts unclaimed environmental subject matter.
